PRESS FOR PAPER MAKING MACHINES

Bernard Abbott Malkin, Lachine, Quebec, Canada, assignor to Dominion Engineering Works Limited, Lachine, Quebec, Canada

Application June 20, 1940, Serial No. 341,514

4 Claims. (Cl. 92—49)

This invention relates to three roll presses and is a continuation, in part, of the invention disclosed in my co-pending application Serial No. 159,939, filed Aug. 19, 1937.

In its preferred embodiment my invention comprises a top press roll and two bottom press rolls arranged with their centers at the corners of a triangle. The first bottom roll is preferably a suction roll while the top roll and the second bottom roll are preferably plain rolls. A pressure applying means is arranged to act against the top roll to give an evenly distributed line pressure between both nips and is controllable to vary the intensity of such pressure. A second pressure applying means is also arranged to act against the top roll to give an additional nip pressure between the top roll and the second bottom roll so that this nip pressure is greater than the nip pressure between the top roll and the first bottom roll. The line of action of the first mentioned pressure applying means is midway between the centers of the two bottom rolls and perpendicular to a line joining said centers. The line of action of the second pressure applying means is substantially along the projection of a line through the centers of the top roll and the second bottom roll. The two pressure applying means are independently controllable so that the intensity of the evenly distributed line pressure obtained through the agency of the first mentioned pressure applying means may be varied without varying the ratio which the nip pressure on the second roll bears to the nip pressure on the first roll or so that the ratio of the two nip pressures can be varied without varying the intensity of the evenly distributed line pressure obtained through the agency of the first mentioned pressure applying means. It is also possible that the pressure applying means described herein may be controlled to vary both the ratio of the nip pressures and the intensity of the evenly distributed line pressure by varying the action of both of the pressure applying means.

Proceeding now to a more detailed description reference will be had to the accompanying drawing, in which

Fig. 1 is an end elevation of a three roll press designed in accordance with this invention.

As shown in the drawing, the first and second bottom rolls 5 and 6 are respectively journaled in suitable bearings 1 mounted on the frame 8. The first bottom roll 5 is preferably a suction roll which may be of any suitable design and serves, in addition to its pressing function, as a convenient means for quickly removing the water

pressed from the paper web during its passage through the first nip of the press. The press felts are generally indicated at 10 and 11 and may be guided and tensioned by a suitable arrangement of guide and stretcher rolls.

The top press roll 12 is positioned between and rests upon the bottom rolls 5 and 6 so that the centers of the three rolls are located at the three corners of a triangle. Each end of the top roll shaft 13 is journaled in a split bearing 14 provided at the lower end of a link 15. The upper end of link 15 is fastened, by a pivot 16, to the end 16a of a pressure applying lever 16. As here shown each lever 16 is intermediately pivoted, as at 17, to a bracket 18 rising from the frame 8 adjacent the suction roll 5. The end 19 of each lever is connected by a link 20 to one end of a lever 21 which is intermediately pivoted to the bracket 18 as indicated at 22. The remaining end of lever 21 is pivoted to the upper extremity of a piston rod 23 having its lower extremity fastened to a piston 24 working in a cylinder 25, the lower portion of said cylinder being pivoted to the frame 8 as indicated at 26 to provide a pivotal axis about which the cylinder is free to oscillate. Pressure fluid, such as air or liquid, is alternately supplied to and exhausted from the upper and lower ends of cylinder 25 through ports 27 and 28 provided for this purpose. The cylinder 25 is preferably connected in circuit with a source of fluid under pressure so that, through the agency of suitable control valves (not shown) pressure fluid may be supplied to the upper end of the cylinder 25 through port 27 and simultaneously exhausted from the lower end of the cylinder through port 28 and vice versa. When pressure fluid is supplied to the upper end of cylinder 25 the resulting downward pressure on piston 24 is transmitted, through the piston rod 23, lever 21, link 20, lever 16 and link 15, to the top roll 12. When the press is in operation the link 15 occupies the inclined position shown in the drawing so that one side of this link is spaced from a shoulder formed by a lateral projection 16c of the pressure applying lever 16. In this connection it will be noted that the centers of the rolls 6 and 12 and the pivot point 16 are aligned so that the line of action of the downward pressure applied to the top roll by the pressure applying levers 16 is along the projection of a line through the centers of the rolls 7 and 12. Consequently, the downward pressure applied to the top roll through the links 15 and pressure applying levers 16 gives a greater nip pressure between the top roll and the second bottom roll 6

as compared with the nip pressure between the top roll and the first bottom roll 5. The intensity of the downward pressure thus applied to the top roll 12 can, of course, be varied by appropriate operation of control valves included in the hydraulic connections between the cylinder 25 and the source of fluid under pressure.

Each of the split bearings 14 in which the top roll 12 is journalled is provided with a downwardly directed lug 30 which is fastened by a coupling link 31 to the upper end of a rod 32. The lower end of rod 32 is attached to a pin extending at right angles to the main portion of the rod to provide an arm 33 which is seated in a notch 34 provided in the lower edge of a lever 35 having one end pivoted to a bracket 36 carried by the frame 8. The remaining end of lever 35 is pivoted to the upper end of a piston rod 37 connected to a piston 38 working in a cylinder 39, the lower end of said cylinder being pivoted to the frame 8 as indicated at 40. Cylinder 39 is provided with ports 41 and 42 which correspond to and serve the same purpose as the ports 27 and 28 of the previously mentioned cylinder 25. Cylinder 39 is also connected in a hydraulic circuit including a source of fluid under pressure so that fluid may be admitted to the upper end of cylinder 39 through port 41 and simultaneously exhausted from the lower end of said cylinder through port 42 and vice versa. When pressure fluid is admitted to the upper end of cylinder 39 through port 41 the downward pressure on piston 38 is transmitted to the top press roll 12 through the agency of piston rod 37, lever 35, rod 32, link 31, lug 30 and bearing 14. It will be noted that the rod 32 and the terminal pivots of the link 31 are aligned with each other and with the central vertical axis of the roll 12. Consequently, it will be seen that the line of action of the downward pressure transmitted to the roll 12 through the agency of the rod 32 is midway between the centers of the two bottom rolls 5 and 6 and is perpendicular to a line joining said centers. It will therefore be seen that when downward pressure is applied to piston 38 the tension developed in the nip pressure rods 32 gives an evenly distributed line pressure on both nips which may be varied in intensity without varying the difference in nip pressure between the first and second nips.

Each of the tension rods 32 is adjustable in length, being made in two sections connected by a turn buckle 32a.

When it is desired to lift the top roll 12 clear of the bottom rolls 5 and 6, this may be accomplished by disrupting the connection between the top roll and the tension rods 32 and supplying fluid to the lower ends of cylinders 25 to force the pistons 24 upwardly. This upward movement of pistons 24 acts through the piston rods 23, levers 21, links 20, pressure applying levers 16 and pressure distributing links 15 to raise the top roll 12 and the latter may be held in its raised position by engaging a hook 43 beneath a portion of pivot 22. In this connection it will be noted that hook 43 is pivoted to a bracket 44 carried by the pressure applying lever 16. It will also be noted that during the upward movement of the levers 16 the lateral projections or shoulders 16c act against the adjacent sides of the pressure distributing links 15 to raise the top roll 12.

If desired, the top roll 12 may be a hollow heated roll to which steam or other heating me-

dium is supplied in any desired or well known manner.

The invention also contemplates the employment of a suction roll as the top roll or second bottom roll of the press in which event the first bottom roll would be a plain roll. These and other desirable modifications are contemplated as falling within the scope and spirit of the invention as defined by the appended claims.

Having thus described my invention, what I claim is:

1. A press for paper making machines comprising a top press roll and two bottom press rolls arranged in triangular formation, pressure applying means acting against the top roll to give an evenly distributed line pressure between both nips and a second pressure applying means also arranged to act against the top roll to give an additional nip pressure between the top roll and the second bottom roll so that this nip pressure is greater than the nip pressure between the top roll and the first bottom roll, said first mentioned pressure applying means comprising a cylinder, a piston working in said cylinder and a pressure transmitting connection through which downward pressure on said piston is transmitted to the top press roll so that the line of action of the pressure thus transmitted is along the projection of a line through the center of the top roll midway between the centers of the two bottom rolls and perpendicular to a line joining the two last mentioned centers.

2. A three roll press comprising a top roll and two bottom rolls arranged in triangular formation and means for exerting downward pressure on the top roll to give a nip pressure between the top roll and the second bottom roll which is greater than the nip pressure between the top roll and the first bottom roll, said means comprising a pair of pivotally mounted pressure applying levers, inclined links connected between the levers and the top roll, said links being pivoted to said levers so that the centers of the pivotal connections between these parts lie on the projection of a line through the centers of the top roll and the second bottom roll, a pair of cylinders, pistons working in said cylinders and pressure transmitting connections between said pistons and said levers.

3. A press for paper making machines comprising a top press roll and two bottom press rolls arranged in triangular formation, pressure applying means acting against the top roll to give an evenly distributed line pressure between both nips and a second pressure applying means also arranged to act against the top roll to give an additional nip pressure between the top roll and the second bottom roll so that this nip pressure is greater than the nip pressure between the top roll and the first bottom roll, said second pressure applying means comprising a pair of pressure applying levers intermediately pivoted to swing about a common horizontal axis located at one side of the top roll, said levers being arranged so that one end of each lever extends inwardly over the first bottom roll while the other end is disposed at the side of the first bottom roll remote from the top roll, means for exerting upward pressure on the last mentioned ends of the levers and pressure transmitting connections through which downward pressure is transmitted to the top roll along the projection of a line through the centers of the top roll and the second bottom roll, said connections comprising pressure transmitting links having their upper ends piv-

oted to said levers and having bearings at their lower ends in which the shaft of the top roll is journalled, said links being inclined from the vertical and being connected between the top roll and the pressure applying levers so that the centers of the pivots at the upper ends of the links lie on the projection of a line through the centers of the top roll and the second bottom roll.

4. A press for paper making machines comprising a top press roll and two bottom press rolls arranged in triangular formation, a movable pressure applying member, pressure transmitting connections through which downward

pressure is transmitted from said member to the top press roll along the projection of a line through the center of the top roll midway between the centers of the two bottom rolls and 5 perpendicular to a line joining the two last mentioned centers, a second movable pressure applying member and pressure transmitting connections through which downward pressure is transmitted from said last mentioned member to the top roll along the projection of a line through the centers of the top roll and one of said bottom rolls.
